UNITED STATES PATENT OFFICE.

EMERY J. WILSON, OF CLEVELAND, OHIO, ASSIGNOR TO THE THEW SHOVEL COMPANY, OF LORAIN, OHIO, A CORPORATION OF OHIO.

DIPPER-STICK MOUNTING.

Application filed June 16, 1926. Serial No. 116,403.

This invention relates to a mounting for the dipper stick in the boom of a power shovel and has for its objects the provision of a mounting which will allow a maximum

5 swing of the stick, and the provision in such a mounting of anti-friction but positive and structurally superior means for maintaining proper alignment of the stick throughout all of its possible operating positions.

10 The exact nature of the invention is described in the following specification having reference to the accompanying drawing, in which Fig. 1 is a side elevation of a complete power shovel showing the positioning of the 15 dipper stick mounting and its operative relation with the other members of the shovel structure; Fig. 2 is a view looking down on the boom, and showing a section of the dipper stick positioned in the mounting; Fig. 3 is an 20 enlarged section along the line 3—3 of Fig. 2 and Fig. 4 is a similarly enlarged section along the line 4—4 of Fig. 1.

The principal parts of the shovel are the 25 driving assembly, generally indicated by the reference numeral 1, rotatably mounted upon the carriage 2, and carrying a boom 3, which in turn carries the dipper 4 by means of the dipper stick 5 supported at its dipper end by suitable tackle; these parts and their 30 general arrangement being well known in the art.

My invention however, is a departure from the usual practice as to the location and arrangement of the dipper stick mounting. 35 The boom is built up of spaced structural members which form a longitudinal opening medially of it, across which, through the members passes a shipper shaft 6 carrying between the members of the boom a crowd pinion 7, and upon an over-hanging end, a 40 sprocket 9 whereby the pinion may be rotated. The side members of the boom are symmetrical about the shipper shaft both longitudinally and laterally, which provides a 45 maximum strength with a minimum of weight. Owing to this central location of the shaft in the side members the top and bottom plates or web members of the boom may be considerably lengthened as the clearance 50 required by the stick is greatly diminished.

The dipper stick carries a rack 8 extending throughout its length and adapted for engagement with the crowd pinion whereby longitudinal motion may be imparted to the 55 stick regardless of its angular position with

respect to the boom; suitable means, to be described, being provided for maintaining proper contact between the rack and pinion and proper alignment of the stick.

In the boom opening surrounding the shaft 60 6 on each side of the dipper stick and pinion is a generally circular surfaced casting member 10; each of these castings being secured with the boom as by a bolt 11 passing through the entire assembly, suitable inwardly extending bosses 18 upon the thus paired members 10 providing the proper clearance between the inner faces of the members to closely maintain proper alignment of the dipper stick between them and yet allow free 65 swing of the dipper stick. Other securing means, such as the bolted flanges 12 and the bolts 13, may be arranged to assist the bolt 11 in maintaining the proper positioning of the members which are thus made to serve 70 in strengthening the boom.

Inwardly of each of the members 10 and concentric with the shipper shaft there-through is a track 14, and in these paired tracks is arranged to run a backing carriage 80 for the dipper stick as follows: The carriage comprises two roller assembly units circumferentially spaced by the links 15, each of the units comprising the rollers 15^a adapted to ride in the tracks 14, and a roller 16 there-between and on a common shaft 17 therewith adapted to bear upon the back of the stick for maintaining proper relation between the rack 8 and pinion 7.

The result of the arrangement described, 90 which constitutes my invention, is an easily accessible anti-friction backing for the rack 8 in any and every position thereof; a stick positively maintained in alignment by bearing surfaces of large area; and the boom is 95 greatly strengthened, especially at its point of maximum stress. And by the same means a much greater swing of the stick than has heretofore been possible in the art is accomplished.

100 What I claim is:

1. In a dipper stick mounting, a dipper stick, a boom apertured to receive said stick, guide members between said stick and adjacent surfaces of said boom, a shaft passing 105 through said boom and members, a pinion on said shaft, a rack upon said stick in engagement with said pinion, and means carried by said members for maintaining engagement between said rack and pinion. 110

2. In a dipper stick mounting, a dipper stick, a boom apertured to receive said stick, circular surfaced guide members between said stick and adjacent surfaces of said boom, a shaft passing through said boom and members, a pinion on said shaft, a rack upon said stick in engagement with said pinion, and anti-friction means carried by said members for maintaining engagement between said rack and pinion. 35
- 5 3. In a dipper stick mounting, a dipper stick, a boom apertured to receive said stick, guide members between said stick and adjacent surfaces of said boom, a shaft passing through said boom and members, a pinion on said shaft, a rack upon said stick in engagement with said pinion, and anti-friction means carried by said members for maintaining engagement between said rack and pinion. 40
- 10 4. In a dipper stick mounting, a dipper stick, a boom apertured to receive said stick, guide members between said stick and adjacent surfaces of said boom, a shaft passing through said boom and members, a pinion on said shaft, a rack upon said stick in engagement with said pinion, and anti-friction means carried by said members for maintaining engagement between said rack and pinion. 45
- 15 5. In a dipper stick mounting, a dipper stick, a boom apertured to receive said stick, guide members between said stick and adjacent surfaces of said boom, and secured upon said boom to reinforce the same. 50
- 20 6. In a dipper stick mounting, a dipper stick, a boom apertured to receive said stick, guide members between said stick and adjacent surfaces of said boom, and inwardly projecting bosses upon said members for maintaining clearance for said stick. 55
- 25 7. In a dipper stick mounting, a dipper stick, a boom apertured to receive said stick, guide members between said stick and adjacent surfaces of said boom, and inwardly projecting bosses upon said members for maintaining clearance for said stick, and arranged to be cleared by said stick during operation thereof. 60
- 30 8. In a dipper stick mounting, a dipper stick, a boom apertured to receive said stick, guide members between said stick and adjacent surfaces of said boom, and inwardly projecting bosses upon said members for maintaining clearance for said stick, and arranged to be cleared by said stick during operation thereof. 65
- 35 5. In a dipper stick mounting, a dipper stick, a boom apertured to receive said stick, guide members between said stick and adja-

In testimony whereof I hereby affix my signature.

EMERY J. WILSON.
